GEORGES EUGÈNE GAIFFE, OF PARIS, FRANCE.

TRANSFORMER EMPLOYED IN HIGH-FREQUENCY-CURRENT CIRCUITS.

No. 877,319.

Specification of Letters Patent.

Patented Jan. 21, 1908.

Application filed November 8, 1904. Serial No. 231,892.

To all whom it may concern:

Be it known that I, GEORGES EUGÈNE GAIFFE, of 9 Rue Méchain, in the city of Paris, Republic of France, electrical engineer, have invented Improvements in or Connected with Transformers Employed in High-Frequency-Current Circuits, of which the following is a full, clear, and exact description.

10 High potential transformers, alternating current transformers, Ruhmkorff coils, etc., and in general any source of continuous or alternating current which are employed in a circuit producing oscillations of high frequency are themselves traversed by currents of high frequency since the secondary of a transformer is itself a capacity which charges and discharges in accordance with the oscillations taking place in the main high frequency circuit. Hence electric oscillations are produced within the secondary of the transformer and these spread lengthwise of the winding at a certain velocity. From this it results that at the same instant, two 25 adjacent points of the winding may be at very different potentials and this difference of potential may amount to the total difference of potential of the transformer. A high potential transformer is thus incapable of 30 working at high frequency, unless special precautions are taken.

The present invention has for its object to provide means whereby the above mentioned disadvantage may be remedied.

35 This invention consists essentially in the employment, with the object of damping the oscillations of high frequency which tend to traverse the said transformer, of resistances either alone or in conjunction with capacities 40 connected to the extremities of the secondary of the transformer.

The accompanying drawing diagrammatically illustrates the principle of the invention, by way of example.

45 Figure 1 illustrates an apparatus serving to explain the phenomenon to which are due the dangers peculiar to the working of sources of high potential owing to the production of oscillations of high frequency. 50 Fig. 1^a shows the resistances applied to the two extremities of the secondary within the transformer itself. Fig. 2 shows the resistances applied to the two extremities of the secondary outside the transformer. Figs. 3 55 and 4 show similar arrangements of the re-

sistances and in addition the capacities above referred to. Fig. 5 shows a modification of Fig. 4. Fig. 6 is a section taken through a cell showing in detail one of the resistances for protecting the apparatus against extreme 60 differences in potential.

The same letters of reference indicate the same parts in the several figures.

Referring to Fig. 1, which serves to explain the phenomenon which takes place, *a* is the secondary winding of a high potential transformer; *d* is the high-frequency installation. The point *n* of the spark-gap circuit follows the variations of potential produced by the oscillating discharge of the condensers of circuit *d*. Thus if the source has charged the plate *h* of condenser *i* to a potential of +100,000 volts, that the periodicity of the oscillations in the circuit *d* is one million, this shows, supposing the damping of the electric 70 oscillations to be *nil*, that the point *n* passes from the potential +100,000 volts to the potential -100,000 volts with a frequency of 1,000,000 cycles per second, *n* being the extremity of the winding *a* of the transformer. 75 The primary winding *p* is used to energize the secondary winding by induction in the usual manner. While these oscillations are being produced the source tends to maintain at the extremities of the transformer a potential 80 which may be considered as constant during a short interval of time, which potential is +100,000 volts; thus there is at certain moments a potential of -100,000 volts at one 85 of transformer terminals, while the source tends to maintain the potential thereat, at +100,000 volts. If we consider a point *m* situated in one of the last coils of the winding *a*, it is such that the self-induction of circuit *m*, *n* is sufficient to prevent the rapid variations of difference of potential from +100,000 90 to -100,000 volts at the one terminal of the spark gap from affecting the potential of the point *m* which remains at a potential of +100,000 volts, less the feeble electro-mo- 95

100 tive force due to the winding *m*, *n*. Between the points *m* and *n* there are thus instantaneous differences of potential of from +100,000 to -100,000 volts, or 200,000 105 volts, that is to say the total potential-difference of the transformer and this constitutes the danger.

The safety device shown in Fig. 1^a is constituted by the application to the extremities of the secondary *a* of the transformer, or 110

windings b , c (sufficiently well insulated to withstand the high pressures brought into play) having a resistance capable of damping the high-frequency oscillations, whatever 5 may be their wave length and consequently of keeping the dangerous portion comprised between the extremity n (Fig. 1) of the transformer and point m , independent of the variations of potential of the spark gap. d indicates the high-frequency circuit. The 10 resistance and the insulation of the windings b , c may be obtained in any suitable manner, as for example by the alternate or inter-winding of a wire of high resistance with any suitable insulating material. The secondary of 15 the transformer thus comprises at each of its extremities a winding whose resistance and insulation are of much greater value than those required in ordinary industrial applications.

In the modification represented in Fig. 2 the safety device is constituted by two safety-resistances b , c placed in front of the secondary of the transformer upon the respective conductors constituting the prolongations of the extremities of the said secondary. These resistances b , c are so constituted as to damp all oscillations and are sufficiently well insulated to prevent sparking 20 between any two points of the resistances. To each resistance b , c there may be connected a capacity e , f as shown in Figs. 3 and 4, which is supplemental to the capacity of the transformer winding itself. These capacities 25 e , f , may be of any suitable kind and are so connected that the charging oscillations will tend to traverse the resistance whatever may be the position of this resistance relatively to the transformer. Fig. 3 shows the arrangement of the capacities e , f in the case when 30 the safety-resistances are placed in the interior of the transformer, while Fig. 4 shows the arrangement when the resistances are placed externally to the transformer. The 35 addition of this capacity permits either, with a given resistance, of augmenting the damping effect produced by this resistance or (if a stated amount of damping is rendered necessary by the conditions of working), of diminishing the resistance necessary for producing 40 such damping.

Fig. 5 represents a modification of Fig. 4. The capacities e , f (Figs. 3 and 4) in this arrangement consist of any suitable condenser 45 g sufficiently well insulated. The function of the capacity in the arrangements shown in Figs. 4 and 5 may be explained as follows: The capacities e , f (Figs. 3, 4 and 6) are grounded as shown. Instead of these capacities I sometimes use a condenser g , as indicated in Fig. 5. The capacities or the condenser, as the case may be, serve as a reservoir which becomes charged to the same difference of potential as that of the source 50 and this reservoir can only discharge itself.

slowly through the windings b and c , so that when point n of the spark-gap passes to the potential - 100,000 volts (to revert to the figures before mentioned), the potential of the point n' varies but very little inasmuch as 55 the condenser g can only discharge but a very small quantity during the millionth of a second during which the oscillation exists, and consequently between the point m (see description of Fig. 1) and point n' only such slight differences of potential will exist as will exclude all possibility of danger to the insulation.

It is to be observed that the resistance may be replaced by self-inductive devices or by 60 the combination of resistance and self-induction, and generally by any means of retarding the discharge of the condensers and damping the return oscillations.

The safety device of this invention is suitable for use with all high-potential transformers, alternating-current transformers, Ruhmkorff coils, etc., and generally with any source of supply of a continuous or alternating current employed in circuits in which 65 oscillations of high frequency are liable to be produced, either continuously (as in wireless telegraphy and medical coils) or intermittently as in industrial installations.

Claims.

1. The combination of an oscillation circuit, a secondary winding for energizing the same, and means for protecting said secondary winding from potential strains accumulating within said oscillation circuit.
2. The combination of an oscillation circuit, a secondary winding for energizing the same, and resistances inserted intermediate of said oscillation circuit and said secondary winding for protecting the latter from potential strains of said oscillation circuit.
3. The combination of an oscillation circuit, a secondary winding for energizing the same, resistances inserted intermediate of said oscillation circuit and said secondary winding and preventing disruptive discharges from taking place from said oscillation circuit to said secondary winding, and condensers for deadening the electric oscillations tending to take place in the secondary winding and capable of producing said disruptive discharges.

110

4. The combination of an oscillation circuit, a secondary winding disposed in conductive relation thereto and resistances connected at the ends of said secondary winding, 115 and high potential insulation for preventing the escape of current from said resistances.

120

5. A safety device for protecting high potential transformers against oscillation of high frequency, comprising a secondary winding, resistances connected with the ends thereof, electric capacities joined intermediate said resistances and said secondary winding.

125

6. A safety device for protecting high

95
